UNITED STATES PATENT OFFICE.

EMILE RIMAILHO, OF PARIS, FRANCE, ASSIGNOR TO COMPAGNIE DES FORGES ET ACIERIES DE LA MARINE ET D'HOMECOURT, OF PARIS, FRANCE.

WHEELED GUN-CARRIAGE WITH WIDE SCOPE OF FIRE FOR FIELD-ARTILLERY.

1,285,390.

Specification of Letters Patent. Patented Nov. 19, 1918.

Original application filed June 17, 1914, Serial No. 845,578. Divided and this application filed May 26, 1917. Serial No. 171,207.

To all whom it may concern:

Be it known that I, EMILE RIMAILHO, a citizen of the French Republic, and residing in Paris, France, 98 Rue de la Victoire, consulting engineer, have invented certain new and useful Improvements in and Relating to Wheeled Gun-Carriages with Wide Scope of Fire for Field-Artillery, of which the following is a complete specification.

10 In those gun carriages which at the moment of firing are in contact with the ground at four points, the latter points are represented on the one hand by the lower part of each of the wheels (hereinafter called the "axle-wheel" system) and on the other hand by the ends of two trails (hereinafter called the "trail" system), special arrangement having to be made to impart to the gun carriage with a view to road service, 15 the usual disposition of a carriage with single central block trail, short in order to facilitate the turning of the vehicle and nevertheless long enough to insure the stability of the carriage when firing is carried 20 on without the trails having been placed right and left of the central line of the gun carriage.

The object of the present invention is the 25 construction of a gun carriage in which the above purposes are secured by providing the front part of the "trail" system with extensions, lengthening out either by sliding or by double jointing on the said front part.

On the drawings annexed:—

30 Figure 1 is a plan of the gun carriage according to a first working construction with arrangement for folding the trail of the carriage, these trails being opened for firing,

Fig. 2 is a view similar to Fig. 1 with the 35 trails in closed position for road transit,

Figs. 3 and 4 respectively show an elevation and longitudinal section of a trail,

Figs. 5 and 6 represent the application of the folding trails to gun carriages.

45 Fig. 7 is a general plan of the axle and the trails of another working construction, the trails being in open position for firing,

Fig. 8 is a general plan with part section of the axle and the trails, the latter being in 50 closed position for road travel and hooked to a forecarriage,

Figs. 9 and 10 show a side elevation and a longitudinal section respectively of a trail,

Fig. 11 is a rear end view representing one of the trails in closed position for road 55 travel, the other trail being in an open position for firing,

Fig. 12 is a rear end view representing the "trail" system in one of the extreme positions of transverse direction relatively to 60 the axle.

As the gun carriage which we are considering must, with a view to road service, exhibit the usual arrangement of a carriage with single central trail, these trails have 65 been designed according to the arrangement shown on Figs. 1 to 4 in the first working construction. The male part 1 of a ball and socket joint, which engages in a lodgment in the axle, is fixedly connected with the front 70 part 22 of the "trail" system. This front part expands in horse-shoe form, carrying two branches 23 cut away so as to form lodgments, in which the trails proper 6 and 7 can 75 slide.

Each of the sliding carriage trails is guided in the corresponding branch 23 of the horse-shoe part 22 by lateral walls 24 and 25 of this branch which determine the direction of the corresponding trail for the 80 road and firing positions respectively. In the firing position I (Fig. 1) a centering pin 27 of the trail occupies the middle of a guide groove 28 cut in the branch 23, so that the trail can undergo a pivotal movement about this pin 27. In the firing position the trail is rigidly connected with the branch 23 by a rotating bolt 35 which engages into its end suitably notched for that 85 purpose.

In order to pass from the firing position to the road position the connection effected by the bolt 35 is first done away with, then the trail is made to pivot around the pin 27 until a rib 29 of this trail is brought into 90 the prolongation of the groove 28, this position II (Fig. 1) being defined by a stop 30 carried by the branch 23. The trail is then made to slide until a lapping stop 31 of the trail comes to bear on the end of the 100 branch 23 (position III). At this moment a second centering pin 26 is in the middle

of the groove 28. The trail is then made to pivot about this pin as a center bringing into engagement a dove-tail recess 32 of the trail, (position IV) on a projection 33 of the 5 axle. For the road position each trail is thus hooked to the axle, so that this part directly bears the traction strains during transit.

When the trails occupy position IV on 10 Fig. 1, their butts come into contact on the longitudinal axis of the carriage (Fig. 2) and they can be bolted together by any suitable device and the usual trail ring can be hooked to the wagon as in the case of an 15 ordinary carriage (Fig. 2).

To lengthen out the trails and bring them from the road position (Fig. 2) into the firing position (Fig. 1) the operations are carried out inversely.

20 Figs. 1 to 4 represent the folding arrangement of the trails adapted for the case when the male part of the ball and socket joint of the gun carriage is carried by the "trail" system. Figs. 5 and 6 represent the 25 same folding arrangement of the trails adapted for the case when the male part of the ball and socket joint is carried by the "axle-wheel" system.

In the second working construction of 30 carriage, in order to insure the guidance of the trails during the operations of folding and unfolding, suitably inclined guide shoes 72 (Figs. 7 and 8) are placed on the axle, the side face 73 of each of them forming 35 a guide for the corresponding half-trail in the road position as shown on the left in Fig. 11.

Each of the half-trails 74 is guided in 40 the horseshoe part by faces 75 and 76 (Figs. 7 and 8) for the opened-out position, and locking can be effected by means of a rotary half-spindle 77 as shown for the aforesaid constructions.

On the upper and lower faces of the recess 45 in which each half-trail fits, there is mounted a pivot 78 (Figs. 7 and 10) in engagement with a slide 79 lodged in a longitudinal groove 80 cut in the half-trail, so that the half-trail is guided in its sliding by the 50 groove 80 forming the sockets for the slides 79, the movement in both directions being limited by the ends of the groove.

On the outer side face of each half-trail there is provided a rectilinear groove 81 into which, for the closed position of the 55 trails, a pin 82 fixedly connected with the corresponding guide-shoe 72 can engage. A recess 83 cut away at the end of this groove presents a shape corresponding to that of the pin 82 thus allowing the locking indicated in Fig. 8.

To bring the half-trails from the firing position I indicated in full lines on Fig. 7, to the road position IV indicated in chain 60 lines on Fig. 7, the locking half-spindle 77

is first made to turn, so as to free the end of the half-trail, then the latter is made to turn around the pivots 78 until its lateral face abuts against the side face of the pin 82 of the corresponding guide-shoe, position 70 II, this pin then entering the groove 81. The half-trail is then made to slide in order to bring it into position III, the bottom of the groove 80 abutting against the slides 79. At this moment the recess 83 is in front of 75 the pin 82, so that by continuing the movement toward the interior of the trail butt, the recess 83 is made to pass on to the pin 82, thus locking the trail on to the carriage (position IV).

The two half-trails being brought into the same position, they are fastened together by a spike before being hooked to the wagon.

What I claim is:—

1. A wheeled gun carriage consisting of 85 an axle wheel and a trail frame coupled together through a ball and socket joint, and trail beams pivotally mounted on the trail frame.

2. A wheeled gun carriage comprising an 90 axle wheel frame, a trail frame coupled thereto through a ball and socket joint, trail beams mounted on said trail frame to slide on said trail frame, and means carried at the rear ends of the trail beams for connection to the fore carriage. 95

3. A wheeled gun carriage comprising an axle wheel frame, a trail frame, trail beams slidably and pivotally mounted on said trail frame, and means for locking the trail beams 100 in their active and inactive positions.

4. A wheeled gun carriage comprising an axle wheel member and a trail frame, said trail frame having diverging tubular members, forming guides for the trail beams, 105 sliding pieces mounted in the tubular members and provided with a pivot pin, the trail beams having longitudinal grooves in their upper and lower faces to receive the pivots, and guide shoes mounted on the axle, each 110 guide shoe having a spur on one side, a groove formed in the outer side face of the corresponding trail beams and terminating in a recess to lock the trail beams in road positions, but permitting pinning in such 115 positions.

5. A wheeled gun carriage comprising an axle wheel member, and a trail frame member, said trail frame provided with diverging 120 tubular arms provided with a housing at their free ends within which trail beams are mounted to swing and have longitudinal sliding movement, and supporting guides carried by the axle wheel member to receive the trail beams when so slid. 125

6. A wheeled gun carriage comprising an axle wheel member and a trail frame member, said trail frame having diverging tubular arms, angularly disposed housings at the free ends of said arms, whereby the trail 130

beams mounted in the arms are adapted to have a sliding and swinging movement, and means carried by the trail beams and co-operating with the aforesaid housings to limit the sliding movement of the beams through the same.

In testimony whereof I have hereunto set

my hand at Saint Etienne (France) this fourth day of May 1917.

EMILE RIMAILHO.
